UNITED STATES PATENT OFFICE.

GEORGE FRANCIS DOWNS, OF BUFFALO, NEW YORK.

CLEANING DEVICE FOR ROTARY KILNS.

1,220,827.

Specification of Letters Patent. Patented Mar. 27, 1917.

Application filed October 5, 1916. Serial No. 123,940.

To all whom it may concern:

Be it known that I, GEORGE F. DOWNS, a citizen of the United States, and a resident of Buffalo, in the county of Erie and State 5 of New York, have invented certain new and useful Improvements in Cleaning Devices for Rotary Kilns; and I do hereby declare that the following is a full, clear, and exact description thereof, reference being had to 10 the accompanying drawings, and to the letters of reference marked thereon, which form a part of this specification.

This invention relates to an improved device for cleaning rotary kilns or furnaces 15 and consists of the matters hereinafter described and more particularly pointed out in the appended claims.

In the treatment of ores and of other 20 readily fusible materials in a rotary kiln, particles or small masses of the fused, gum-like substance collect upon and adhere to the brick lining of the kiln as the material travels toward the discharge end of the kiln. These particles or masses build up upon 25 themselves and, as the material under treatment is subjected to a continuously increasing temperature as it travels toward the discharge end of the kiln (where the maximum heat zone is located) this formation or coating becomes of greater thickness toward the 30 discharge end of the kiln, which, if the formation is not prevented, will become choked.

The object of the invention is to provide a 35 cleaning device of simple and economical construction for rotary kilns, which may be introduced into the kiln from time to time during its operation and may be used to remove the fused, gum-like accretions from the lining of the kiln and thus prevent the 40 aforesaid choking formation. The cleaning device may be and is in the preferred construction, electrically operated, and is located at the discharge end of the kiln in such manner that it may be inserted through the 45 hood and caused to penetrate the kiln to the required distance to reach the zone where the accretion formation begins. As stated, it may be used without interrupting the operation of the kiln and it is also capable, 50 as will appear, of cleaning the kiln when the kiln is not in operation.

The many advantages of my improvement will appear as I proceed with my specification.

55 In the drawings:

Figure 1 is a view representing in longi-

tudinal section the discharge end of a rotary kiln (which may be of any familiar type) with my improved cleaning device, shown in side elevation, applied thereto. 60

Fig. 2 is a view representing the cleaning device alone and on an enlarged scale.

Fig. 3 is a top plan view of the cleaning device.

Fig. 4 is a view representing a transverse 65 section through the device in a plane indicated by the line 4-4 of Fig. 2.

Fig. 5 is a view representing a second transverse section, in a plane indicated by the line 5-5 of Fig. 2. 70

Fig. 6 is a view representing a partial longitudinal section through Fig. 3 in a plane indicated by the line 6-6 of Fig. 3.

Fig. 7 is a view representing a vertical section through Fig. 1 in a plane indicated by the line 7-7 of Fig. 1. 75

Fig. 8 is a detail, sectional view on an enlarged scale, illustrating the action of the cutting tool.

Fig. 9 is a perspective view of the cutting 80 tool.

Referring now to that embodiment of my invention illustrated in the drawings:—20 indicates the discharge end of a rotary kiln of any familiar construction, and 21, the rear 85 end wall of the pit below the kiln, which wall provides a support for the rear end of the kiln; 22 indicates the discharge pit which receives the conglomerated, molten ore or other material that has been treated 90 in the kiln; 23 indicates a non-rotative, closing hood at the discharge end of the kiln, mounted on rollers 24; 25 is a platform which provides a top wall for the discharge pit 22; and 26 indicates the fuel opening in 95 the closing hood 23.

My improved cleaning device consists of a suitable frame or bed to be located at the discharge end of the kiln and of a reciprocable, rigid, tool-holding member or bar 100 mounted on said frame and capable of penetrating the kiln in a line parallel to the inclined axis thereof and carrying one or more tools or cutters adapted in effect to mill or machine the accretions from the lining of 105 the kiln. The tool holding member is preferably made hollow, so that it may be water cooled, and as illustrated herein is in the form of a girder built of channels or plates, so as to provide the necessary rigidity to 110 withstand the thrust of the tools, with economy of weight and material.

28 indicates the rigid reciprocable member, which, as shown, is a hollow girder, rectangular in cross-section and built of two horizontally spaced, vertically arranged 5 channel bars 29, 29, a top horizontally arranged channel bar 30 and a bottom horizontal plate 31, riveted together. Said girder is mounted on a frame or bed 33 which is supported on a base or foundation 34, resting upon and secured to the platform 25. The base 34 is preferably made of reinforced concrete. The frame or bed 33 consists of longitudinally extending, parallel, spaced side members 35, 35, which are braced 10 apart and held in the required upright relation by means of transverse end plates 37, 37 and an intermediate plate 38.

The reciprocable bar 28 is mounted in the space between the side frame members 35, 20 35 as follows:—At the front end of the frame or bed 33 there is a rotative shaft 40 which is provided with suitable bearing at its ends in the side frame members 35. A roller 41 is fixed on said shaft and is provided with parallel, laterally spaced bearing 25 rims 42, 42. The bottom of the girder 28 has laterally spaced, parallel plates 31^a, 31^a fixed to its bottom plate 31. Said bearing plates ride upon the bearing rims 42, 42 and 30 provide a bearing surface for the girder.

Near the rear end of the bed or frame 33, a second horizontal shaft 43 is suitably mounted in the side frame members 35. Said shaft has fixed to it a bearing roller 35 44, also having bearing rims 45, 45 which are engaged by the bearing plates 31^a, 31^a on the girder. The last named bearing roller 44, in the space between the bearing rims 45, is provided with a rack wheel 46 and the 40 girder, between the two bearing plates 31^a, 31^a is provided with a rack plate 47, having teeth which are engaged by the aforesaid rack wheel 46. Manifestly, a rotative movement of the roller 44 in one direction or the 45 other will impart a longitudinal reciprocatory movement to the girder.

In order to retain the girder in position with the rack plate 47 on its bottom surface in proper engagement with the rack wheel 46, 50 a top roller 48 is placed above the roller 44, the same being fixed on an idle shaft 49, having suitable bearings in the side frame members 35. This roller engages and bears upon the top of the girder. Stops 50, 50 are fixed to 55 the top of the girder at points longitudinally spaced from each other at a distance equal to the intended full limit of travel of the girder, and these stops are adapted for engagement with the roller 48.

60 To resist the thrust of the tool or tools (presently to be described) at the forward end of the girder or tool-holder and to maintain the girder in alinement, I provide anti-friction guide-devices for it near the forward and rear ends of the frame. Flanged

rollers 51, 51 are mounted at the sides of the girder just forward of the shafts 45, 49 with their flanges engaging the top of the girder and their bodies engaged with the top flanges of its two upright channel bars 70 29, and rollers 52, 52 are mounted at the sides of the girder near the forward end of the bed and just to the rear of the forward supporting roller 41, with their flanges engaging the top faces of the bottom flanges 75 of said channel bars and their bodies in engagement with the edges thereof. The rollers 51 are mounted on studs 51^a, fixed to the top of the side frame members of the bed. The rollers 52 are mounted on pins 52^a which 80 are fixed in the ends of a cross bar 53 secured in any convenient manner to the side members of the frame.

The following gearing and power mechanism is provided to drive the girder or tool holder. On the shaft 43, at one side of the bed, there is fixed a large gear 55 which meshes with a small gear 56, on a cross shaft 57 mounted in the side frame members 35 in a suitable manner. At the other 90 end of the shaft 57, on the opposite side of the frame or bed, there is fixed a large gear 58 which meshes with a second small gear 59 fixed on a cross shaft 60. On this shaft is mounted a pulley 61. Said pulley is connected by a belt 62 to a motor or engine, in this case preferably an electric motor 63, which rests upon the platform 25 in a position to the rear of the base 34. This motor is reversible and is provided with a suitable 100 control so that it may be operated to drive the girder either forward or backward, as desired or required in the cleaning operation.

There is provided at the rear of the base 105 34, a supplemental support for the girder 64, comprising a suitable frame resting upon the platform 25 and a roller 65 of the same type as the other rollers, and provided with bearing rims to engage the bearing plates 110 31^a on the bottom girder to support it when it is fully withdrawn from the kiln. The girder penetrates the kiln through an opening 70 in the hood 23 which opening may be closed by means of a counter-weighted 115 sliding door 71 when the girder is withdrawn.

At the forward end of the girder are carried the tool or tools which are intended to engage the fused or conglomerated material 120 on the inner surface of the kiln and remove the same from said surface. As shown, there are six of these tools, 72, which are constructed and mounted as follows: Each tool consists of a bar 73, extending at right 125 angles to the tool holder 28, and having a counter-weight 74 at one end, and of a cutter head 75 at its other end which is located adjacent to the inner surface of the kiln. This cutter head acts as a chisel or 130

as a milling tool in removing the accretions from the surface of the kiln. The cutter head 75 is pivotally connected at 76 to the bar 73 and is provided with a lip or stop 77 (see Fig. 8) which is adapted to engage a shoulder 78 at the end of the bar which limits the movement of the cutter head on the bar in the direction of the rotation of the kiln, so as to make it act as one with the bar when the edge of the cutter is operatively engaged in doing its work. A movement in the opposite direction will act to swing the cutter head upon its pivot and allow the tool to slide without effect over the inner surface of the kiln. A bearing sleeve 79 made rigid with the bar 73, is placed intermediate the cutter head and the counter-weight and preferably nearer the cutter head. By means of this bearing sleeve, the tool as a whole is rotatively mounted on a rod or shaft 80 which is supported on suitable bracket arms 81, 81 fixed to the top of the girder or tool holder near the forward end thereof.

The tool holder or girder 28 being hollow, is capable of being water cooled and to this end a pipe 83 is led forward through its center, being fixed in position by means of suitable blocks or bracket arms 84 near the forward and rear ends of the girder. This pipe projects through the rear open end of the girder and is there connected to a flexible tube or hose 85 which leads from any suitable source of water supply. The pipe is provided with discharge openings 83^a near and at its forward end, so that the cold water is discharged at the forward end of the hollow interior of the girder. The girder, which is arranged parallel to the inclined axis of the kiln, is therefore inclined toward its rear end, so that the water discharged into the girder will naturally flow toward its discharge end. The water flows out of the girder at its rear end over a discharge lip 28^a whence it is received in a trough or other suitable device 86 by which it is conveyed to a sewer or other place of disposal. This trough extends the full length of the travel of the girder and is supported in any convenient fashion (not shown) on the platform 25.

The operation of the cleaning device is apparent from the foregoing description. An operator, located at the discharge end of the kiln, has the inner surface thereof under constant observation through the door opening 70. As the fused material begins to collect and accumulate on the lining of the kiln during its operation, he starts the motor so as to drive the girder longitudinally through the door opening into the kiln. This brings the tool heads into engagement with the accretions on the lining of the kiln as indicated in Fig. 7, and the rotative movement of the kiln in engagement

with the tool edges causes said accretions to be milled or scraped off and thus removed.

In case the tool edge strikes a larger or harder lump or projection of the accumulated material than it is able to take care of at once, the manner of mounting the tool together with its counter-weight, permits the tool to yield as indicated in Fig. 8. This prevents breaking of the tool, and in case the mass is not removed the first time in the first reciprocation of the girder through the kiln, it will be acted upon and removed upon the second movement.

The girder is caused to move back and forth by means of the motor, during the rotation of the kiln, so that it acts in effect, as before stated, to "machine" or "mill" the accumulations from the interior surface of the kiln. Instead of the tools thus far referred to, however, the end of the girder 28 may be provided with a single, fixed cutting member 90 which will act as a plow or longitudinally operating chisel to remove the accumulations as the girder is reciprocated back and forth through the kiln. This kind of tool is more adapted for use when the kiln is not in operation, when it may be caused to reciprocate with the kiln in one position, to remove the accumulations in one line, after which the kiln may be shifted on its axis to bring a new surface into position whereupon the tool may be caused to reciprocate and remove the accretions in the next adjacent line and so on.

While in describing my invention, I have referred to many details of mechanical construction and arrangement, which are manifestly capable of modification, it is to be understood that the invention is in no way limited thereto except as may be pointed out in the appended claims.

I claim as my invention:

1. A cleaning device for kilns and the like comprising, a frame, a tool-holding member reciprocable on said frame in a line parallel to the axis of the kiln to be cleaned and of a length to penetrate the kiln to a point remote from said frame, means for holding said tool-holding member rigidly to said frame throughout its reciprocatory movement and one or more tools carried at the forward end of said tool-holding member.

2. A cleaning device for kilns and the like comprising, a frame, a tool-holding member reciprocable on said frame in a line parallel to the axis of the kiln to be cleaned and of a length to penetrate the kiln to a point remote from said frame, devices connecting said tool-holding member with said frame and adapted to resist the thrust against said tool-holding member and to hold it rigidly to said frame throughout its reciprocatory movement, and one or more tools carried at the forward end of said tool-holding member.

3. A cleaning device for kilns and the like comprising, a frame, a tool-holding member reciprocable on said frame in a line parallel to the axis of the kiln to be cleaned and of a length to penetrate the kiln to a point remote from said frame, antifriction devices on said frame adapted to engage said tool-holding member and resist the thrust against it, and to rigidly hold it in alinement throughout its reciprocatory movement, and one or more tools carried at the forward end of said tool-holding member.
4. A cleaning device for kilns and the like comprising, a frame, a tool-holding member reciprocable on said frame in a line parallel to the axis of the kiln to be cleaned and of a length to penetrate the kiln to a point remote from said frame, gearing intermediate said frame and said tool holding member for driving said tool-holding member, and one or more tools carried at the forward end of said tool-holding member and extending laterally therefrom.
5. A cleaning device for kilns and the like comprising, a frame, a tool-holding member reciprocable on said frame in a line parallel to the axis of the kiln to be cleaned and of a length to penetrate the kiln to a point remote from said frame, means for holding said tool-holding member rigidly to said frame throughout its reciprocatory movement, gearing for reciprocating said tool-holding member, a reversible power member for driving said gearing, and one or more tools carried at the forward end of said tool-holding member.
6. A cleaning device for kilns and the like comprising, a frame, a tool-holding member reciprocable on said frame in a line parallel to the axis of the kiln to be cleaned and of a length to penetrate the kiln to a point remote from said frame, one or more tools carried at the forward end of said tool-holding member, and means for water cooling said tool holding member.
7. A cleaning device for kilns and the like comprising, a frame, a tool-holding hollow bar reciprocable on said frame in a line parallel to the axis of the kiln to be cleaned and of a length to penetrate the kiln to a point remote from said frame, one or more tools carried at the forward end of said bar, a pipe extending through said bar and provided with discharge openings, and means for supplying water to said pipe.
8. A cleaning device for kilns and the like comprising, a frame, a tool-holding hollow bar reciprocable on said frame in a line parallel to the axis of the kiln to be cleaned and of a length to penetrate the kiln to a point remote from said frame, one or more tools carried at the forward end of said tool holding bar, a pipe extending into said bar and provided with discharge openings, a flexible pipe connected to said first named pipe, and means for receiving and conducting away the water discharged from the rear end of said hollow bar.
9. A cleaning device for kilns and the like comprising, a frame, a tool-holding member reciprocable on said frame in a line parallel to the axis of the kiln to be cleaned and of a length to penetrate the kiln to a point remote from said frame, and one or more tools carried at the forward end of said tool-holding member and extending transversely thereof.
10. A cleaning device for kilns and the like comprising, a frame, a tool-holding member reciprocable on said frame in a line parallel to the axis of the kiln to be cleaned and of a length to penetrate the kiln to a point remote from said frame, and one or more counter-weighted tools pivotally carried at the forward end of said tool-holding member and adapted to swing in a plane or planes extending transversely of said tool-holding member.
11. A cleaning device for kilns and the like comprising, a frame, a tool-holding member consisting of a hollow girder reciprocable on said frame in a line parallel to the axis of the kiln to be cleaned and of a length to penetrate the kiln to a point remote from said frame, said girder having flanges, and antifriction, flanged rollers located at the front and rear ends of said frame and having their flanges and bodies engaged respectively with the tops and edges of the flanges of said girder to resist the thrust of the tools against said girder.
12. A cleaning device for kilns and the like comprising, a frame having longitudinally extending side members, a tool-holding bar reciprocable between the side members of said frame in a line parallel to the axis of the kiln to be cleaned and of a length to penetrate the kiln to a point remote from said frame, longitudinally spaced rollers mounted in said frame and supporting said bar, a top roller mounted in the side members of said frame and located above one of the first mentioned rollers, a rack fixed on the bottom of said bar, a rack wheel rotatively mounted in said frame, and power driven mechanism for rotating said rack wheel in either direction.
13. A cleaning device for kilns and the like comprising, a frame having longitudinally extending side members, a tool-holding bar reciprocable between the side members of said frame in a line parallel to the axis of the kiln to be cleaned and of a length to penetrate the kiln to a point remote from said frame, longitudinally spaced rollers mounted in said frame and supporting said bar, a top roller mounted in the side members of said frame and located above one of the first mentioned rollers,

antifriction devices on the side members of said frame engaged with said bar and adapted to resist the tool thrust against said bar, a rack fixed on the bottom of said bar,
5 a rack wheel rotatively mounted in said frame, and power driven mechanism for rotating said rack wheel in either direction.

14. In a cleaning device of the kind described, in combination with a tool-holding member, a tool pivoted to swing on said tool-holding member in a plane extending transversely thereof, said tool consisting of a bar, a counter-weight fixed to one end of said bar, and a tool-head carried at the
10 other end of said bar.

15. In a cleaning device of the kind described, in combination with a tool-holding

member, a tool pivoted to swing on said tool-holding member in a plane extending transversely thereof, said tool consisting of 20 a bar, a counter-weight fixed to one end of said bar, and a tool-head pivotally carried at the other end of said bar, said tool-head and bar having abutting shoulders adapted to resist the movement of said tool-head 25 relative to said bar in one direction.

In testimony that I claim the foregoing as my invention I affix my signature in the presence of two witnesses, this 2nd day of October, A. D. 1916.

GEORGE FRANCIS DOWNS.
